[57] CLAIM

The ornamental design for interconnect housing for coupling electrical signals between a computer and a control unit, as shown and described.

DESCRIPTION

FIG. 1 is a left, front perspective view of an interconnect housing for coupling electrical signals between a computer and a control unit showing our new design;

FIG. 2 is a right, front perspective view thereof;

FIG. 3 is a front elevational view thereof;

FIG. 4 is a left side elevational view thereof, on an enlarged scale;

FIG. 5 is a right side elevational view thereof, on an enlarged scale;

FIG. 6 is a rear elevational view thereof;

FIG. 7 is a left rear perspective view thereof;

FIG. 8 is a right rear perspective view thereof; and,

FIG. 9 is a top view thereof.
